RACK FOR HEATING TEXTILE FABRICS DRAPE THEREOVER

William J. Kenney, Franklin Park, Ill., assignor to
Leonard Friedman, Highland Park, Ill.

Filed Jan. 11, 1971, Ser. No. 105,783

Term of patent 7 years

Int. Cl. D23—03

U.S. Cl. D23—77

Fig. 1

Fig. 2

Fig. 3

FIG. 1 is a perspective view of a rack for heating textile fabrics draped thereover, embodying my new design;

FIG. 2 is an enlarged end elevational view thereof, the rack being broken away for convenience of illustration; and

FIG. 3 is a reduced front elevational view thereof.

The hooks and cord are shown in broken lines for illustrative purposes only.

I claim:

The ornamental design for a rack for heating textile fabrics draped thereover, as shown and described.
